UNITED STATES PATENT OFFICE

2,185,903

GAS DISTRIBUTOR FOR BURNER OUTLETS

Henry E. Stein, Sr., Columbus, Ohio, assignor to
Quad Stove Manufacturing Company, Columbus,
Ohio, a corporation of Ohio

Application March 11, 1938, Serial No. 195,342

6 Claims. (Cl. 158—116)

This invention relates broadly to improvements in gas burners, and, in its more specific aspects, is particularly concerned with the provisions of an improved orificed gas distributor adapted for use in the outlet or outlets of such burners, an object of the invention being to provide a gas distributing element which will permit of complete combustion of the gaseous fuels discharged from the burner throughout the entire combustion range or flame height of the burner.

In certain localities, it is an accepted practice to utilize butane, propane or mixtures thereof, as domestic heating fuels for employment in gas-burning appliances. Considerable difficulty has been encountered in adapting gas burners of the type utilized in room heaters of the radiant or circulating types, water heaters and other forms of gas burners to the use of these heavier hydro-carbon fuels, particularly in the matter of obtaining uniform and efficient combustion at all flame heights of the burner. Manufacturers of gas burners usually modify orifice diameters when it is known that the burners are to be employed in connection with fuels of the character above noted. However, changing the orifice area does not result in obtaining the desired combustion at all rates of fuel delivery. It has been observed that when using butane as a fuel, and with the burner turned down to produce a low fire, the fuel will often burn with a yellow luminous flame, producing smoke or carbon formation, or, again, the same condition in other burners is present under medium or high-fire conditions.

To correct this situation and to overcome the objections noted in the operation of burners using butane or propane, or mixtures thereof, as the gaseous fuel, the present invention provides in the outlet of the burner a gas-distributing or diffusing element formed to comprise an orificed body through which the fuel issues for combustion purposes, the upper or outer portion of said body being formed with an axially disposed cylindrical extension of reduced diameter as compared with the orificed body portion, so that gaseous fuel issuing from the outlet of the burner through the orifice or orifices formed in said body will be prevented from immediately merging by the presence of the cylindrical extension, to the end of permitting sufficient atmospheric air to combine with the gas to insure complete and clean combustion thereof at all flow rates and without objectionable smoke or soot formation.

Further objects and advantages will become apparent as the description proceeds.

55 In the accompanying drawing:

Figure 1 is a view in front elevation and partially in vertical section of gas burner apparatus formed in accordance with the present invention;

Figure 2 is a vertical transverse sectional view taken through the apparatus on the plane indicated by the line II—II of Figure 1;

Figure 3 is a top plan view disclosing the fuel distributing and diffusing elements forming the present invention in the outlets of a gas burner;

Figure 4 is a perspective view of one of the fuel diffusing and distributing elements.

While the invention is susceptible to various modifications and alternative constructions, I have shown in the drawing and will herein describe in detail the preferred embodiment thereof, but it is to be understood that I do not thereby intend to limit the invention to the specific embodiment disclosed, but desire to cover all modifications and alternative constructions falling within the spirit and scope of the invention as expressed in the appended claims.

In the drawing, I have illustrated a form of gas burner quite generally used in the construction of room heaters of the radiant type. It will be understood, however, that the invention is not limited to burners of this specific design but is applicable to the many different types of burners used in various types of heating equipment.

Referring more particularly to the drawing, the numeral 1 designates the gas-supply manifold of the burner, the manifold being provided at spaced intervals with orifice spuds 2 arranged to direct gas in a fine stream upwardly under customary pressures. Connected with the manifold 1 as at 3 is a mixer-tube casting 4, which is provided with a plurality of vertically extending passages 5 which are arranged in vertical registration with the orifices of the spuds 2. The lower ends of the passages terminate in outwardly flaring curved mouths 6, which are spaced from the spuds 2 so that atmospheric air may be drawn into said passages by the inspirating action of the gas streams issuing under high velocity from the spuds 2.

Within the passages 5, the fuel gas and atmospheric air combine to produce a combustible mixture in the customary manner. In this instance, the upper end of each of the passages 5 is laterally branched as at 7 to produce dual outlets 8 in the top of the casting 4. By this branching of the upper end of each of the passages 5 to cause horizontal travel of the gas-air mixture, further turbulence of the mixture is secured to produce more efficient carburetion, as will be un-

derstood by those skilled in the art. Above the casting 4, a support 9 is provided for a plurality of upwardly extending perforated clay radiants 10, the latter being heated to incandescence by the combustion of the fuel mixture which takes place within the confines of said elements.

The construction so far described is quite widely used in room heaters of the radiant type and, therefore, no claim is made to the same per se. The particular construction with which the present invention is concerned is the form and arrangement of the gas distributing and diffusing element 11, disclosed particularly in Figure 4. One of these elements is arranged in each of the outlets 8 of the burner and comprises a cylindrical body formed preferably from hardened volcanic lava. Although I do not specifically limit myself to the use of the material specified, I have obtained the best results with its use since the lava is highly refractory and is not affected by the high temperatures incident to burner operation.

The cylindrical body 12 of each element is carefully cut to be frictionally received and supported by the inner surfaces of the outlets 8, as shown in Figure 1, and the body is further provided with alternate deep and shallow slots 13 which extend vertically of the body from top to bottom thereof in radial order. The fuel mixture issues from the outlets 8 through the slots 13 so that combustion takes place around the upper surfaces of the elements 11 and within the confines of the radiants 10. Due to the alternate arrangement of the deep and shallow slots, the air is permitted to filter into the flame issuing from the burner outlet and prevent the flame from coning over into a solid mass and burning without sufficient oxygen to produce smokeless combustion. The slots 13 are but illustrative of but one form of orifice formation and it is obvious that other types of orifices may be used.

An important feature of the present invention resides in forming with the upper axial portion of the body 12 a short cylindrical vertical stud 14, the latter being integrally formed with the body 12. The diameter of the stud 14 is such that the same lies within the inner ends of the slots 13. I have found the elements 11 constructed as disclosed to be particularly useful in the burning of butane or of other hydrocarbon fuel mixtures wherein butane or propane is a predominating ingredient.

The stud 14 apparently keeps separated for a time the gases issuing from the upper ends of the slots 13, preventing such gas streams from immediately merging after issuing from the slots 13 and forming a center pocket of reduced pressure. With the inclusion of the stud 14 in each of the elements, it is believed that the gas streams are kept separated for a sufficient length of time to admit of the combining of secondary air therewith to provide for clean combustion so that a blue flame is produced at all rates of burner operation and the presence of a yellow luminous flame avoided.

The inclusion of the stud or cylindrical extension 14 thus maintains uniform combustion of the fuel specified, or gaseous fuels containing the same at varying rates of delivery of such gaseous fuels to the burner, enabling the latter to operate under low, medium or high flame producing conditions with clean, efficient combustion and with substantially complete absence of smoke or soot formation.

What is claimed is:

1. As a new article of manufacture, a gas distributing and diffusing element for gas burner outlets comprising a cylindrical body formed peripherally with radially disposed relatively spaced alternate deep and shallow slots, the latter passing through said body from top to bottom thereof, and a cylindrical extension arising axially from the top of said body, said extension being disposed within the inner confines of said slots.

2. In a gas burner, a mixing tube provided with a gas outlet, a gas distributing and diffusing element arranged in said outlet, said element comprising a cylindrical body provided with a plurality of spaced vertically extending slots for the passage of gas through said outlet, and a cylindrical stud formed with and projecting upwardly from said body at the center thereof, said stud being disposed within the flame when the burner is in operation.

3. A gas distributing and diffusing element for gas burner outlet comprising a thick disk-like body having a plurality of circumferentially spaced vertically extending slots formed in the periphery thereof, and a stud of reduced diameter projecting from one face of said body, the longitudinal axis of said stud and body being in alignment.

4. In a gas burner of the type having a mixing tube provided with a gas outlet, a gas distributing and diffusing element arranged in said outlet, said element comprising a thick disk-like body having a plurality of circumferentially spaced vertically extending passages formed in the periphery thereof, and a stud of reduced diameter projecting from the upper face of said body, said stud being disposed above the upper limits of said mixing tube.

5. A gas distributing and diffusing element for gas burner outlets comprising a cylindrical body reduced at one end to form a pair of adjoining concentric sections, the larger of said sections being formed beyond the confines of said smaller section with a plurality of circumferentially spaced passages, the longitudinal axes of which are parallel to that of said body.

6. A gas distributing and diffusing element for burner outlets consisting of an integral body having a pair of cylindrical portions of different diameters disposed end to end, the portion having the larger diameter being formed with a plurality of circumferentially spaced longitudinally extending ports beyond the confines of the other section.
